UNITED STATES PATENT OFFICE.

SPENCER OTIS, OF CHICAGO, ILLINOIS, ASSIGNOR, BY MESNE ASSIGNMENTS.
TO NATIONAL DUMP CAR COMPANY, A CORPORATION OF MAINE.

CAR.

No. 858,013.

Specification of Letters Patent.

Patented June 25, 1907.

Application filed September 15, 1906. Serial No. 278,649.

To all whom it may concern:

Be it known that I, SPENCER OTIS, a citizen of the United States, residing at Chicago, in the county of Cook and State of Illinois, have invented certain new and useful Improvements in Cars, of which the following is a specification.

The invention relates principally to the under framing for cars.

10 It relates particularly to cars having longitudinal center sill mechanism and trussed intermediate longitudinal sills on opposite sides of the center sill mechanism, provided with transverse needle beams supported by 15 the trussed intermediate sills, and all forming a trussed longitudinal beam mechanism constituting the main supporting framework of the car.

20 The principal object of the invention is to provide a simple, economical and efficient car.

A further object is to provide a car having longitudinal center sills with intermediate sills suitably trussed and having needle 25 beams supported by such intermediate sills and extending under the center sills adapted to transfer a portion of the weight of the load from the center sills to the trussed intermediate sills, and all so connected as to form an 30 efficient longitudinal trussed beam mechanism forming the main supporting framework for the car.

35 A further object is to provide an efficiently trussed longitudinal beam mechanism so constructed and arranged upon suitable bolsters as to be adapted to carry the weight of the load, and provide ample space at each side of such longitudinal beam mechanism to permit the dumping of the load between such 40 longitudinal beam mechanism and the side frames.

Other and further objects of the invention will appear from an examination of the drawings and the following description and claims.

45 The invention consists in a supporting framework having longitudinal center sill mechanism mounted in suitable bolsters and trussed longitudinal sills on opposite sides thereof provided with needle beams supported by the trussed sills and extending beneath the center sill mechanism, adapted to transfer a portion of the weight of the load from the longitudinal center sill mechanism to

such trussed sills, and all forming the main supporting framework of the car. 55

It consists further, and finally, in the features, combinations and details of construction hereinafter described and claimed.

In the accompanying drawings—Figure 1 is an end elevation of a car constructed in accordance with my improvements; Fig. 2 a side elevation of one end of the car; Fig. 3 a central sectional elevation of the opposite end of the car not shown in Fig. 2; Fig. 4 a transverse sectional elevation, taken on line 4 of Fig. 3, looking in the direction of the arrow; and Fig. 5 a plan view of the supporting framework of the portion of the car shown in Fig. 3 with the fixed and swinging or dumping floor sections removed. 70

In constructing a car in accordance with my improvements, I provide a supporting framework having a pair of longitudinal center sills *a* formed of channel irons arranged with their upper and lower flanges extending 75 outward laterally. Intermediate longitudinal sills *b* are mounted on a plane slightly below the level of the center sills and formed of channel irons having their lateral top and bottom flanges extending inward toward 80 the longitudinal center of the car. These longitudinal sills extend from end sill to end sill through suitable openings *c*, *d*, *e* and *f* in body bolsters *g*, which are supported in any ordinary manner upon trucks *h*, which may 85 be of any ordinary and well known type.

Each of the intermediate sills above described is provided with a truss member *i* which is oblong in cross section and has its greatest width in a vertical plane. These 90 truss members extend longitudinally of the car below the intermediate sills, and at each end thereof they extend upward and longitudinally of the car at an incline having their opposite end portions extending through the 95 openings *c* and *f*, respectively, in the body bolsters and secured to the intermediate sills beyond such body bolsters by means of suitable rivets.

Struts for the longitudinal trusses are 100 formed of vertical center pieces 21 and angle iron side members 22 and 23, having their laterally projecting flanges secured to such center pieces by means of rivets, as shown in Fig. 2. The upper end portions of such angle 105 iron side members extend upward and longi-

tudinally of the car in opposite directions at an angle forming Y-shaped struts, the upper oppositely inclined portions of which are secured to the outside of the intermediate longitudinal sills by means of rivets 24 and the lower portions of which are secured to the lower chords of the trusses by means of rivets 25. Mounted between the trusses opposite these strut members and independently thereof are transverse needle beams *j*, which have their opposite ends secured to the inner sides of the lower chords of the trusses above described, by means of angle irons *k*. These needle beams extend transversely beneath and support the longitudinal center sills, so as to transfer a portion of the weight of the load from such center sills to the trussed-side or intermediate sills which support the needle beams. The upper edges of these needle beams are provided with angle irons *l* forming lateral strengthening flanges adapted to be secured to the center sills, if desired, and the trussed sills may be secured to the bolsters by means of rivets 26, a plate 27 being also mounted upon and secured to the longitudinal sills adjacent to each bolster. Transverse beams *m* are provided, formed of side members 30 having a central web portion 31 therebetween and each having a T-shaped top member 32, the depending central flange of which extends between the side members of such beams, being secured thereto by means of rivets, the lateral flanges extending outward laterally beyond the sides of such beams. These transverse metallic beams are mounted upon and supported by the longitudinal sills at suitable intervals to permit the swinging of the dumping doors therebetween, as hereininafter described.

A superstructure is provided having side frames *n*, end frames *o*, swinging dumping bottom sections *p* and a central fixed floor section *q*. The swinging dumping bottom sections are pivotally secured to the framework of the car by means of shafts *r*, which extend longitudinally from end to end of the car near the center thereof. The swinging dumping bottom sections are operated by means of hand wheels *s* upon operating shafts *t*, having worms *u* in engagement with worm wheels *v* upon the door supporting and operating shafts. Shafts *w* extend longitudinally of the car beneath the doors and are reciprocatingly mounted upon upwardly and outwardly inclined tracks *y*, such shafts being connected to the door supporting shafts *r* by means of cranks 2 and pivoted connecting arms 3. The rotation of the hand wheels in one direction will, therefore, move the shafts *w* toward the center of the car to lowered position, permitting the doors to drop to open inclined dumping position, and the rotation of the operating wheels in the opposite direction will raise the doors and move the shafts

w into position to support the outer edges of the door, as shown in Fig. 4.

Suitable end sills are provided, the main body portions of which are formed of channel irons 5 having bottom flanges 6 and top flanges 7 extending outward laterally from the vertical web portions of such channel irons endwise of the car, and a top plate 8 is secured to the upper sides of the channel iron members of such end sills and also secured to the end board of the car by means of an angle iron 9. These end sills are secured to intermediate longitudinal sills by means of gusset plates 28 and to the center sills by means of angle plates 29. Dead blocks 10, which may be of any ordinary and well known construction, are mounted upon the outside of the channel iron members of the end sills between the upper and lower flanges thereof, and such channel iron members are each provided with a central notch 11 through which the draw-bar shank extends.

A carrier arm 12, formed of an angle iron with its horizontal flange 13 extending outward from its upper edge, is secured to the channel iron member of each end sill, so as to extend across the lower side of the opening or notch, such carrier arm being secured to the channel iron member by means of bolts or rivets 14, so as to support the draw-bar shank 15. A supporting arm 16 also extends across the lower edge of the notch and is secured by means of rivets 17 to the lower flange of each channel iron member.

The end frames and side frames of the car are formed of planks and the corners are strengthened by means of angle iron corner plates 18. The side frames are provided with metallic side stakes 19 mounted on the inner sides thereof over the transverse beams and having lateral flanges secured to the side boards, the transverse web portions of such side stakes extending downward at an incline and being secured at their bottom ends to the transverse beams by means of angle plates 20.

I claim:

1. In a car, the combination of longitudinal center sill mechanism, trussed longitudinal sills on opposite sides thereof, and transverse beams extending beneath and supporting such longitudinal center sill mechanism and supported by the trussed longitudinal sills.

2. In a car, the combination of a pair of longitudinal center sills, trussed longitudinal sills mounted upon opposite sides thereof, transverse needle beams supported by such trussed sills and extending beneath and supporting the longitudinal center sills, and body bolsters upon which such longitudinal sill mechanism is supported.

3. In a car, the combination of a pair of longitudinal center sills, trussed longitudinal sills mounted upon opposite sides thereof,

- transverse needle beams supported by such trussed sills and extending beneath and supporting the longitudinal center sills, struts connecting the top and bottom chords of the trusses, and body bolsters provided with openings through which all of such longitudinal sills extend. 5
4. In a car, the combination of longitudinal center sill mechanism, longitudinal sills mounted on opposite sides thereof, body bolsters upon which such sills are supported, truss members extending longitudinally of the sills over the supporting portions of the bolsters and secured to the portions of the sills which extend endwise beyond the bolsters, and needle beams extending transversely beneath the center sill mechanism and secured to and supported by the trussed longitudinal sills. 15
5. In a car, the combination of longitudinal center sill mechanism, trussed longitudinal sills on opposite sides thereof, transverse beams secured to such trussed sills and extending beneath and supporting the longitudinal center sill mechanism, end sills having their main body portions formed of channel beams provided with flanges extending outward endwise of the car and having notches for admitting the draw-bar shank, a 25 carrier arm secured to such channel beam member of each end sill and extending across the notched portion thereof, and body bolsters upon which such longitudinal sills are mounted. 30
6. In a car, the combination of longitudinal center sill mechanism, longitudinal sills mounted on opposite sides of such center sill mechanism, end sills to which such longitudinal sills are secured, body bolsters upon 35 which the longitudinal sills are supported, truss members having their end portions secured to the longitudinal sills between the bolsters and end sills and extending over the
- sill supporting portions of the body bolsters, and needle beams secured to such truss members and extending beneath and supporting the longitudinal center sill mechanism. 45
7. In a car, the combination of longitudinal center sill mechanism, trussed longitudinal sills mounted on opposite sides of such center sill mechanism, needle beams supported by such trussed longitudinal sills and extending beneath and supporting the center sill mechanism, and struts mounted upon the outside of such trussed beams opposite the 50 ends of such needle beams. 55
8. In a car, the combination of longitudinal center sill mechanism trussed longitudinal sills mounted on opposite sides of such center sill mechanism, needle beams supported by such trussed longitudinal sills and extending beneath and supporting the center sill mechanism, and struts having angle iron side members mounted upon the outside of and secured to such trussed longitudinal 60 beams. 65
9. In a car, an underframe having a main supporting truss mechanism formed of a plurality of tension members, needle beams connecting such tension members and supported 70 thereby, and integral longitudinal channel beams supported by the needle beams. 75
10. In a car, the combination of supporting bolsters, longitudinal center channel beams supported by the bolsters, longitudinal intermediate channel beams supported by the bolsters, longitudinal tension members directly supporting the intermediate channels between the bolsters, and needle beams supported by the tension members and supporting the center channels between the 80 bolsters. 85

SPENCER OTIS.
